UNITED STATES PATENT OFFICE.

WILLIE D. WHITNEY, OF HOLLY, NEW YORK, ASSIGNOR TO THE "1900" WASHER CO., OF BINGHAMTON, NEW YORK.

WASHING-MACHINE.

No. 889,166.

Specification of Letters Patent.

Patented May 26, 1908.

Application filed June 28, 1907. Serial No. 381,345.

To all whom it may concern:

Be it known that I, WILLIE D. WHITNEY, a citizen of the United States, residing at Holly, in the county of Orleans and State of New York, have invented a new and useful 5 Washing-Machine, of which the following is a specification.

This invention relates to washing machines, in which the clothes are confined between 10 two rubbing members, one of which oscillates with respect to the other to secure the desired rubbing action, and one of which moves toward and from the other for the purpose of alternately squeezing and releasing 15 the clothes, and thus forcing the suds through them.

The principal object of the invention is to improve and simplify machines of this type, and to materially reduce the expense of construction, and at the same time to better 20 control the oscillatory action of the movable member than is possible with the constructions now in use.

With these and other objects in view, as will more fully hereinafter appear, the invention 25 consists in certain novel features of construction and arrangement of parts, herein-after fully described, illustrated in the accompanying drawings, and particularly pointed 30 out in the appended claims, it being understood that various changes in the form, proportions, size and minor details of the structure may be made without departing from the spirit or sacrificing any of the advantages 35 of the invention.

In the accompanying drawings:—Figure 1 is a sectional elevation of a washing machine provided with an operating and power transmitting mechanism constructed and arranged in accordance with the invention. Fig. 2 is an elevation of the mechanism, showing the oscillatory member raised to its full height. Fig. 3 is a sectional plan view on the line 3—3 of Fig. 2, showing in dotted 45 lines the movement of the supporting link.

Similar numerals of reference are employed to indicate corresponding parts throughout the several figures of the drawings.

In the drawings, 10 and 11 represent two 50 members, both of which are provided with rubbing surfaces. One of said members is movable in an oscillatory path with respect to the other, and one of the members is movable toward and from the other. In the

present case the upper disk 10 is shown as 55 stationary, being held by a vertically adjustable bar 12 that is carried by a frame 13 secured to the standards or legs 14, while the member 11 constitutes a clothes container or tub, and is movable in an oscillatory path, 60 and is also arranged to reciprocate vertically.

The supporting standards or legs 14 are connected at the top by a suitable spider frame 15, having sockets for the reception of the upper ends of the legs, and the central 65 or hub portion of this spider 15 carries a vertically disposed stationary pin 17, which pin fits within a collar 18 that is provided with a number of branched arms 19 that are permanently secured to the bottom of the mov- 70 able member, in this instance the tub.

The tub and collar 18 are free for oscillatory movement on the pin 17, and this movement may be accomplished by grasping the tub when the device is to be manually oper- 75 ated, or any suitable motor mechanism may be employed for the purpose.

Extending from the spider frame 15, and preferably forming an integral part thereof, is an arm 20 that inclines outward from the 80 axis of the pin 17 and is provided at its other end with a rounded seat grooved at 21 for the reception of the upper hooked end 22 of a link 23, and the lower end of said link is turned to form an eye 24 that extends 85 through an opening formed in a lug 25 projecting laterally from the lower end of the collar 18, that side of the collar from which the lug projects being provided with a tapering recess 26 to permit the convenient intro- 90 duction of the eye and to allow free movement of the collar 18 through approximately an arc of one hundred and eighty degrees.

When the parts are in the position of rest, the link 23 is approximately parallel with the 95 inner face of the arm 20, and the bottom of the eye 24 is but very slightly spaced from the top of the spider 15. As soon as the tub is turned with the pin 17 as an axis, the link is swung around with the grooved seat 21 as 100 a center of movement, the eye 24 describing an arc, the center of which is the axis of the pin 17. As the lug 25 moves out of the vertical plane of the arm 20 and the link 23 assumes the inclined position, the link will 105 naturally elevate the collar 18, and the latter will continue to move upward, carrying with it the tub until the tub has moved through

an arc of approximately ninety degrees from its initial position of rest, the link at this time assuming the position shown in full lines in Figs. 2 and 3, and further movement in this direction is stopped by the fact that there is then direct tensional strain exerted through the link 23 between the arm 20 and the lug 25.

The movement of the tub is not in practice carried on to such an extent that the link 10 will form a direct and positive stop, but on the contrary the movement is gradually checked as the tub approaches its limit, owing to the fact that the force required to turn the tub is increased in proportion to the 15 distance traveled. At first the lift exerted by the link is almost direct, but as the link moves gradually toward the horizontal, its effectiveness is gradually decreased, until the force required to move it is greater than 20 would be ordinarily exerted in the manual operation of the device, so that the tub is naturally released before being brought to a full stop. The weight of the tub causes it to 25 descend by gravity, and the link then sinks down gradually toward the initial position shown in Fig. 1, and swings beyond this position owing to the acquired momentum, and as the operator reverses the thrust on the tub, the latter will be carried in the opposite 30 direction, while the link 23 is moved toward the dotted line position shown in Fig. 3, where the operation is repeated and the tub again released and carried downward beyond the center through its momentum.

35 By the employment of a single link in which the points of attachment of the link are in different vertical planes at different distances from the axis of oscillation, it is found that the tub may be operated with 40 less power, and with greater freedom of movement, while at the same time, the initial expense is much less than in machines of this class where vertical, or approximately vertical pairs of links are employed for the 45 same purpose.

I claim:—

1. In a washing machine, a supporting frame, a stationary vertically disposed pin carried thereby, an oscillatory washing member carried by the pin and free for vertical movement, and an inclined link forming a pivotal connection between the frame and the washing member and serving to impart

vertical movement to the latter during the oscillatory movement. 55

2. In a washing machine, a supporting frame or standard, a stationary vertically disposed pin carried thereby, a tub, a sleeve secured to the tub and receiving said pin, the sleeve being free for oscillatory and vertical movement on the pin, a fixed frame, and a single inclined link having a pivotal connection with the frame and with the sleeve, and serving to impart vertical movement to the sleeve as the latter is oscillated. 60 65

3. In a washing machine, a plurality of standards or legs, a spider frame connecting the upper ends of the same and provided with an outwardly extended arm, the upper end of which is provided with a rounded 70 grooved seat, a vertically arranged pin rigidly secured to the spider, a tub, a sleeve secured to the bottom of the tub and free for oscillatory and vertical movement on the pin, said sleeve having a laterally projected perforated lug, and an inclined link having at one end an eye passing through the perforated lug, the upper end of said link being hooked and fitting within the grooved seat, said link serving to impart vertical movement to the sleeve as the latter is oscillated. 75 80

4. In a washing machine, a pair of rubbing members, one of which may be oscillated with respect to the other, and one of which is movable toward and from the other, a frame, 85 a fixed pin carried thereby, a sleeve carried by one of the rubbing members and free for oscillatory and vertical movement on said pin, an inclined link, the lower end of which is connected to the sleeve, and a fixed support on which the upper end of the link may swing, said link being arranged to move from an inclined position toward a horizontal plane to form a fixed stop for limiting the oscillatory movement of the sleeve, the link 90 95 serving to raise the sleeve during such oscillatory movement, and acting with gradually decreasing force as the movement progresses.

In testimony that I claim the foregoing as my own, I have hereto affixed my signature 100 in the presence of two witnesses.

WILLIE D. WHITNEY.
